CLAIM

The ornamental design for a straw cap, as shown and described.

DESCRIPTION

FIG. 1 is a top, front and right side perspective view of a straw cap showing my new design shown in the closed position;

FIG. 2 is a bottom, front and left side perspective view thereof;

FIG. 3 is a left side elevation view, the right side being a mirror image thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a cross-sectional view taken along line 8-8 of FIG. 6;

FIG. 9 is a cross-sectional view taken along line 9-9 of FIG. 6;

FIG. 10 is a top, front and right side perspective view of a straw cap showing my new design shown in the open position;

FIG. 11 is a bottom, front and left side perspective view thereof;

FIG. 12 is a left side elevation view, the right side being a mirror image thereof;

FIG. 13 is a rear elevation view thereof;

FIG. 14 is a front elevation view thereof;

FIG. 15 is a top plan view thereof;

FIG. 16 is a bottom plan view thereof;

FIG. 17 is a cross-sectional view taken along line 17-17 of FIG. 15; and,

FIG. 18 is a cross-sectional view taken along line 18-18 of FIG. 15.
